UNITED STATES PATENT OFFICE.

CHARLES McINTIRE, OF NEWARK, NEW JERSEY.

BRACELET.

SPECIFICATION forming part of Letters Patent No. 259,187, dated June 6, 1882.

Application filed January 28, 1882. (No model.)

To all whom it may concern:

Be it known that I, CHARLES McINTIRE, of Newark, in the county of Essex and State of New Jersey, have invented a new and useful Improvement in Bracelets, Rings, and Ear-

5 Rings, of which the following is a specification.

My invention relates to an improvement in joint-bracelets, &c., in which the opening is by a lateral movement of the closing ends of 10 the sections; and it consists in the devices substantially as hereinafter set forth.

Figure 1 is a plan or side view, partly in section. Fig. 2 is a view from the inside of the bracelet, showing a stop arrangement in 15 the joint. Fig. 3 is a detailed view. Fig. 4 is a perspective view of the joint ends of the bracelet detached.

In my construction I make a spring, A, the ends of which to extend through about half the 20 length of each section of the bracelet, usually of twisted steel wires, being itself set on a twist, which, when put in the joint portion of a bracelet, forces the two closing ends of the sections B C together laterally, when they will ordinarily 25 lap onto each other side by side, as at L. To secure the joint the section B has near the joint end a fixed collar, D, and in the end a notch, E, taking out a quarter (more or less) of the end. The section C is provided with an 30 inner tube, F, made to enter and turn loose in the end of section B, and a stop projection, G, on one side of the tube, made to enter the notch E for the purpose of regulating the distance the bracelet may be opened. The notch 35 and stop are so arranged that when the stop strikes one side of the notch it will leave the closing ends of the bracelet just at the point of contact or of closing against each other, and the other side of the notch will engage the 40 stop when the bracelet is opened as far as required for putting on or taking off—usually about one-quarter open; or, instead of the ends of the braceletlapping onto the side of each other in closing, the one side of the notch

E may be so arranged that it will engage the 45 stop just at the point when the two ends will be on the same line, the ends being ornamented and made to just meet each other—too short to lap.

When the spring is in place and the joint 50 ends together, the stop resting in the notch, a slide, H, is put over the joint and soldered or brazed to the collar D. The opposite end of the slide is provided with an inner flange, I, made to catch against a fixed collar, K, on 55 the end of section C; and this connection holds the joint ends together, making a swivel-joint, the sections being left to swing laterally in opening and closing the bracelet. This spring is not necessarily of wires twisted together, 60 for a single steel wire having in it the requisite twist will perform the same service set forth, making a bracelet entirely free from a liability to work open and be lost from the wrist of the 65 wearer.

I have described bracelets only; but my invention has equal adaptation to rings and ear-rings embraced in this application.

I claim—

1. In a bracelet, the combination of the section B, provided with the fixed collar D; and the section C, provided with the tube F and collar K, the spring A, and the slide H, having the flange I, adapted to slip onto the section C, so that the flange I shall engage the 70 collar K, and the opposite end of said sleeve or slide be soldered fast to the collar K, all substantially as and for the purpose specified.

2. The combination of the section B, having the collar D and notch E, the section C, carrying the collar K and tube F, said tube supporting the stop projection G, the slide H, with its flange I, and the spring A, all substantially as and for the purpose set forth.

CHARLES McINTIRE.
